US00D998848S

(12) **United States Design Patent** (10) **Patent No.:** **US D998,848 S**
(45) **Date of Patent:** **** Sep. 12, 2023**

(54) **LAMP**

(71) Applicant: **E. MISHAN & SONS, INC.**, New York, NY (US)

(72) Inventor: **Mohan Rajasekaran**, Watertown, CT (US)

(73) Assignee: **E. MISHAN & SONS, INC.**, New York, NY (US)

(**) Term: **15 Years**

(21) Appl. No.: **29/814,250**

(22) Filed: **Nov. 4, 2021**

(51) LOC (14) Cl. **26-05**

(52) U.S. Cl.

USPC **D26/60**

(58) **Field of Classification Search**

USPC ..... D26/24, 51, 55, 60, 61, 62, 64, 72, 80, D26/85, 93, 94, 101, 113, 118, 127 CPC .. F21V 21/08; F21V 21/088; F21V 21/08857; F21L 4/00; F21L 4/02; F21L 4/025; F21L 4/0267; F21W 2131/30; F21W 2131/109

(57) **CLAIM**

The ornamental design for a lamp, as shown and described.

DESCRIPTION

FIG. 1 is a top, front perspective view of a lamp showing the design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

Throughout the figures, broken lines indicate boundaries that form no part of the claimed design.

1 Claim, 7 Drawing Sheets
